UNITED STATES PATENT OFFICE.

CHARLES B. SAMUELS, OF TULSA, OKLAHOMA.

MILK-BOTTLE CARRIER.

1,377,931.

Specification of Letters Patent. Patented May 10, 1921.

Application filed September 9, 1920. Serial No. 409,089.

To all whom it may concern:

Be it known that I, CHARLES B. SAMUELS, a citizen of the United States of America, residing at Tulsa, in the county of Tulsa and 5 State of Oklahoma, have invented new and useful Improvements in Milk-Bottle Carriers, of which the following is a specification.

The object of the invention is to provide 10 simple and efficient means for carrying milk bottles under conditions facilitating the engagement and disengagement thereof and designed particularly for the use of milk distributing or delivering agents; and with 15 this object in view the invention consists in a construction and combination of parts of which a preferred embodiment is shown in the drawings, wherein:—

Figure 1 is a perspective view of the carrier showing in dotted lines the arrangement of the milk bottle necks when engaged thereby.

Fig. 2 is a side view of the device with the jaws deflected in position for engagement 25 with or release of the bottle necks.

Fig. 3 is an end view.

The apparatus consists essentially of a handle or grip 10 from which depend 30 hangers 11 for supporting jaw members 12, said hangers being of looped construction, and the jaw members consisting of bars extended through the loops formed by the hangers and provided with terminal means for embracing and engaging the bottle neck 35 indicated in dotted lines at 13 in Fig. 1. In the construction illustrated the bottle engaging means consist of curved, approximately semi-circular jaws 14 formed by the terminals of the bars constituting the jaw 40 members, and between the hangers the said jaw members are connected by a looped expansion leaf spring 15 having a tendency to spread the jaw members and thus open the terminals thereof for the reception of the 45 bottle necks.

Each hanger is provided in one side with a curved offset 16, the offsets being disposed in opposite relations and serving when the 50 jaw members are moved upward with relation to the hangers to permit of the spreading of the bottle engaging elements through the action of the looped spring. At their lower ends the hangers are contracted to 55 form seats 17 so that when the jaw members are depressed with relation to the hangers and are engaged by said seats they are held

in a closed or folded relation in opposition to the tension of the expansion spring 15 so as to snugly embrace the bottle necks below the beads 13^a thereof, and obviously when 60 bottles are engaged by the jaw members the weight of the former serves to maintain the jaw members in such depressed position in the hangers and preserve an effective engagement of the jaw members with the bottles, while the device is being supported by 65 the grip or handle 10.

When the carrier is lowered to bring the bottom of the bottles into contact with the supporting surface such as a table or the 70 floor the downward pressure of the jaw members upon the shoulders of the bottles serves to move them upward relative to the hangers so as to permit of the expansion incident to the action of the spring, so that 75 the bottles are released and the carrier may then be removed therefrom. On the other hand with one or the other of the jaw members deflected as shown in Fig. 2 which can be effected by a slight upward pressure upon 80 one extremity of either of the jaw members, so as to permit of the spreading action of the spring, the device may be applied to bottles standing in an upright position upon a table or the floor, whereupon a slight down- 85 ward pressure upon the jaw members or a lifting action applied to the grip or handle, with the jaw elements beneath the beads at the upper edges of the bottle necks, will cause a downward movement of the jaw 90 members and a consequent contraction thereof into effectual engaging relation with the bottle necks.

To guard against accidental displacement of the jaw members with relation to the 95 hangers it is preferable to provide each member with a guide pin 18 for engagement with a slot 19 in the adjacent hanger, said slot being preferably formed in that side of the hanger which is opposite to the offset 16 100 as will readily be seen by reference to Fig. 1.

Having described the invention, what is claimed as new and useful is:—

1. A milk bottle carrier having a handle 105 or grip provided with looped hangers, and separable jaw members slidably mounted in said hangers and provided with bottle engaging elements, said hangers being provided at their lower ends with means for 110 holding said jaw members in their bottle engaging relation.

2. A milk bottle carrier having a grip or handle provided with looped hangers, separable jaw members slidably mounted in said hangers and provided with means for engaging interposed bottle necks, said hangers being provided at their lower ends with means for holding said jaw members in their bottle engaging relation and having offsets for permitting the separation of 5 said members. 3. A milk bottle carrier having a grip or handle provided with looped hangers and spring repelled jaw members slidably fitted in said hangers and provided with means 10 for engaging interposed bottle necks, said hangers being provided at their lower ends with seats for holding the jaw members in their bottle engaging relation, and having above said seats offsets for permitting the 15 separation of said members. 4. A milk bottle carrier having a grip or handle provided with looped hangers, jaw members slidably fitted in said hangers and provided with means for engaging in- 20 terposed bottle necks, and a looped expansion spring terminally connected to said jaw members at intermediate points thereof and tending to effect the separation thereof, said hangers being provided at intermediate 25 points with offsets for permitting the separation of the jaw members. 5. A milk bottle carrier having a grip or handle provided with looped hangers, jaw members slidably fitted in said hangers and provided with means for engaging interposed bottle necks, and a looped expansion spring terminally connected to said jaw members at intermediate points thereof and tending to effect the separation thereof, said hangers being provided at intermediate 30 points with offsets for permitting the separation of the jaw members, each of said jaw members being provided with a guide pin operating in a slot in one of the 35 hangers. 40

In testimony whereof I affix my signature.

CHARLES B. SAMUELS.
